CLAMPING MEANS FOR DOORS OF BLAST FURNACE STOVES

Filed April 22, 1947

UNITED STATES PATENT OFFICE

2,605,724

CLAMPING MEANS FOR DOORS OF BLAST FURNACE STOVES

John Frank Baier, Cleveland, Ohio, assignor to
 Arthur G. McKee & Co., Cleveland, Ohio, a corporation of Delaware

Application April 22, 1947, Serial No. 743,016

2 Claims. (Cl. 110—173)

1

This invention relates generally to door clamping means and particularly to clamps for doors of blast furnace stoves.

Prior clamps for doors of stoves for blast furnaces have employed bolts which were stressed in tension when the clamps were holding the doors closed. These bolts were often maltreated by being hammered and bent or subjected to high temperatures and occasionally were so weakened by maltreatment that they broke in use. The failure of those bolts constitutes a serious safety hazard for the gases in the stoves are at temperatures as high as 1800° F. and under considerable pressure. If a door accidentally opens completely, or even only partially, the escaping gases endanger the lives of workmen in the vicinity of the stove. The industry has faced this very real and always present hazard for a long time but has never very satisfactorily solved it heretofore.

I have solved this troublesome and long-continued problem in an effective manner by devising door clamping means including threaded members which are stressed only in compression while serving to press the door into closed position.

Briefly described, the invention comprises a clamp which is engageable with the outer surface of the door and which has arms projecting to beyond the periphery of the door and adjustable compression members between the end portions of the clamp and fittings on the stove for pressing the clamp against the door.

Those skilled in the art will gain a further understanding of this invention upon referring to the drawings accompanying and forming a part of the specification, in which:

Figure 1 is a side elevational view of a portion of a blast furnace stove equipped with one form of apparatus of this invention;

Figure 2 is a view taken on line 2—2 of Figure 1;

Figure 3 is a view taken on line 3—3 of Fig. 1; and

Fig. 4 is a perspective view of the lower door clamp retaining bracket of the apparatus of Fig. 1, the stove on which the bracket is mounted being shown fragmentarily.

The illustrated assembly comprises a blast furnace stove S having a flanged cylindrical portion 10 projecting outwardly from the stove at right angles to the axis of the stove and defining a burner access opening and a stove door seat 12, a door 13 to close said opening, and means M for retaining the door in sealing engagement with

2

seat 12. Means M comprises a clamp 14 having three arms 16, 17 and 18 extending beyond the outer periphery of door 13, two stationary brackets 19 to receive arms 16 and 17, and a latch 20 movable to receive arm 18. Bolts 22 are provided to engage arms 16 and 17 and retain them in position, these bolts being threadwise engaged with brackets 19. A jack screw 24 is threadwise engaged with latch 20 and cooperates therewith to retain arm 18 in position.

Brackets 19 each comprise three metal plates which are welded to the stove and project therefrom adjacent to the burner access opening, and a metal block which is disposed between two of the plates and welded to all three of them. Plates 21 and 21a are spaced apart and parallel to each other and are disposed substantially horizontally, while the third plate 21b is disposed vertically and extends through a slot provided for the purpose in plate 21 and fits in a step cut in one edge of plate 21a. Plate 21b has an upper end with a tongue portion 21c extending upwardly for receipt under flange 12 of the stove, as shown in Fig. 2. Block 21g is located between the outer edges of plates 21 and 21a and is generally L-shaped in plan so that it fits against the outer edge portion of plate 21b between plates 21 and 21a, this said portion being provided with a transverse aperture for registry with a threaded aperture 36 extending through said block at right angles to the plane of said plate 21b to receive a set screw 25 for adjusting the position of clamp 14 relative to door 13. Block 21g is additionally provided in its outer leg portion with a threaded aperture 37 extending toward the stove to receive a bolt 22 to bear against an end portion of clamp 14 to hold the clamp securely against door 13.

Latch 20 is pivotally secured to the stove for movement in the plane of the axis of the cylinder and has a central, elongated, transverse aperture to receive the end portion of arm 18, and a threaded aperture in its free end portion to receive the jack screw 24.

Door 13 is carried by means of a monorail truck 27 mounted on a rail 28, a hanger 30 suspended from the truck and secured to a lug 31 on arm 16, and a hanger 23 secured to the door and suspended from said lug.

In using the apparatus of this invention, truck 27 is moved into position with the clamp 14 and door 13 suspended therefrom, and the door is fitted against the door seat. The upper and lower ends of the clamp are received in brackets 19, while latch 20 is moved into position to receive

the end of arm 18 in its transverse aperture. Bolts 22 are engaged with brackets 19 to press the clamp against the door, and jack screw 24 is engaged with the end of arm 18 and received in latch 20. Prior to the final tightening of the jack screw and bolts, any final adjustments in the position of the clamp may be made by means of set screws 25.

Having thus described the present invention so that those skilled in the art may be able to understand and practice the same, I state that what I desire to secure by Letters Patent is defined in what is claimed.

What is claimed is:

1. In a blast furnace stove having an opening in its side and a door for said opening, the combination of a clamp engageable with the door exterior and including a plurality of arms extending transversely of the door, bracket means including a plurality of brackets projecting from the stove adjacent to said door periphery and having screw-threaded apertures, and means associated with the bracket means for moving the clamp relative to the door and for holding the door in position tightly against the stove and closing said opening, said holding means consisting only of screw compression members screwed into the threaded apertures of the bracket means and extending toward the stove and bearing upon the said arms.

2. In a blast furnace stove having an opening in its side and a door for said opening, the combination of a clamp engageable with the door exterior and including a plurality of arms of sub-

stantially uniform length extending transversely of and projecting beyond the outer periphery of the door, bracket means including a plurality of brackets projecting from the stove adjacent to said door periphery and located to receive end portions of said arms and having screw-threaded apertures, and means associated with the bracket means for moving the clamp relative to the door and for holding the door in position tightly against the stove and closing said opening, said holding means consisting only of screw compression members screwed into the threaded apertures of the bracket means and extending toward the stove and bearing upon the end portions of said arms.

JOHN FRANK BAIER.
